PANEL SUPPORTED TRANSMISSION DUAL SHIFT CONTROL MODULE FOR MOBILE OR STATIONARY EQUIPMENT

Peter D. Adams, La Canada, and Warner R. Lauper, San Pedro, Calif.; said Lauper assignor to Quadrastat Controls Corporation

Filed Apr. 19, 1974, Ser. No. 462,229

Term of patent 14 years

Int. Cl. D15—01

U.S. Cl. D55—1 G

FIG. 2.

FIG. 1.

FIG. 3.

FIG. 4.

FIG. 5.

FIG. 1 is a top plan view of a panel supported transmission dual shift control module for mobile or stationary equipment showing our new design;

FIG. 2 is a side elevational view thereof as seen from the left in FIG. 1;

FIG. 3 is a side elevational view thereof as seen from the right in FIG. 1;

FIG. 4 is a bottom plan view thereof; and

FIG. 5 is an end elevational view thereof, the opposite end being a mirror image of the end shown herein.

We claim:

The ornamental design for a panel supported transmission dual shift control module for mobile or stationary equipment, as shown.
